UNITED STATES PATENT OFFICE.

FRANK F. STARR, OF DAYTON, OHIO, ASSIGNOR TO DELCO-LIGHT COMPANY, OF DAYTON, OHIO, A CORPORATION OF DELAWARE.

MIXTURE-HEATING DEVICE FOR INTERNAL-COMBUSTION ENGINES.

Application filed November 26, 1923. Serial No. 677,136.

To all whom it may concern:

- Be it known that I, FRANK F. STARR, a citizen of the United States of America, residing at Dayton, county of Montgomery, 5 and State of Ohio, have invented certain new and useful Improvements in Mixture-Heating Devices for Internal-Combustion Engines, of which the following is a full, clear, and exact description.
10. This invention relates to electrical heating units for heating a passage through which a fluid is conducted and especially for heating fuel for an internal combustion engine.

15. One of the objects of the present invention is to heat a passage, such as an engine intake, by means of an electrical heating unit which is so constructed that the electrical connections can be made without providing separate holes in the walls of the 20 passage.

25. To accomplish this object, one form of the invention includes an insert located between two ducts such as a cylinder head and a fuel intake pipe. This insert is clamped between the adjacent ends of these ducts and provides a passage connecting them; and supports a heating coil within the passage and terminals extending to the exterior of 30 the insert.

35. Further objects and advantages of the present invention will be apparent from the following description, reference being had to the accompanying drawings, wherein a preferred embodiment of the present invention is clearly shown.

In the drawings:

40. Fig. 1 is a fragmentary cross-sectional view of an engine intake showing the improved heating unit partly in section.

Fig. 2 is a sectional view taken on lines 2-2 of Fig. 1.

Fig. 3 is a sectional view taken on lines 3-3 of Fig. 1.

45. Fig. 4 is a sectional view taken on line 4-4 of Fig. 3.

50. Referring to the drawings, 20 is a cylinder head of an internal combustion engine which carries a valve 21 and is provided with a passage 22. An engine fuel intake 23 provides a passage 24 in alignment with passage 22. Head 20 and intake 23 are provided with flanges 25 and 26, respec-

tively. Bolts 27 extend through flange 26 and are screwed into flanges 25 and 26 for 55 securing these members together. A heating coil unit 30 is clamped between the flanges 25 and 26 by the bolts 27 and forms a gasket between said members.

The heating coil unit 30 comprises a plurality of conductor plates 31 and 32 which are insulated from one another by non-conducting laminae 33. Similar non-conducting laminae are positioned on the outside faces of the conductor plates 31 and 32. The non-conducting laminae 33 are provided with holes 34 having a diameter substantially the same as the diameter of passages 22 and 24 and the conductor plates 31 and 32 are provided with a plurality of arcuate slots 35 and 36. Fuel mixture for the internal combustion engine passes from passage 24 through the holes 34, slots 35 and 36, through the passage 22. Since the plates 31 and 32 are only cut away as at 35 and 36, there are 60 provided central portions 38 having holes 39 in the center thereof which are adapted to receive the reduced portions 40 of spools 41, the ends of which extend through the holes 39 and abut one another. Spools 41 are spirally grooved to receive heating coils 42 and 43, each of which have one end thereof connected respectively to plates 31 and 32 by rivets 46. The other ends of the coils 42 and 43 merge into loops 44 and 45, respectively. A bolt 47 extends through loop 44, spools 41, loop 45 and is adapted when tightened by nuts 48 to hold the spools 41 in position with respect to the plates 31 and 32 and to 65 electrically connect the ends of the coils 42 and 43. 70

Plates 31 and 32 are provided with holes 51 and 52 which are formed symmetrically with respect to vertical line (as seen in Fig. 3) passing through the center thereof, 75 the hole 51 being smaller in diameter than the hole 52. Holes 53 are formed in insulating laminae 33 in direct alignment with holes 51 and 52 and are substantially the same diameter as that of hole 51. Plates 80 31 and 32 are identical in shape and when placed in assembled relation with respect to the laminae 33 one of said plates is reversed so that hole 51 in plate 31 will be located opposite hole 52 on the plate 32. 85 This construction and arrangement permits 90

fastening together the plates 31 and 32 and the insulating laminæ 33 with metallic rivets 55 while at the same time preventing electrical connection being formed between said plates. The center portion of the plates 31 and 32 are located by the spools 41, and the laminæ 33 are connected to the plates 31 and 32 by the rivets 55, each of which extends through the openings 53 of the 10 laminæ 33 and through hole 51 of conductor plate 31 and through a larger hole 52 of conductor plate 32. In this manner the rivet 55 will not be in contact with the conductor plate 32 adjacent the openings 52 (see Fig. 4). Each rivet 55, therefore, locates all of the laminæ 33 with respect to one of the plates 31 or 32. The spools 41 locate the plates 31 and 32 with respect to each other. Therefore displacement of 20 the plates and laminæ 33 is prevented.

Each plate is provided with an ear 60 and when one of said plates is reversed, the ears will be spaced from one another as is clearly shown in Fig. 3. Ears 60 project beyond the flanges 25 and 26 whereby the electrical conductors 61 and 62 can be readily attached thereto. It will be noted that the portions at which the laminæ 33 and plates 31 and 32 are riveted together 30 project beyond the members 20 and 23 and are not engaged thereby, whereby these members 20 and 23 will not have electrical connections with the rivets 55. An electrical circuit to the heating coils includes conductor 61, plate 31, rivets 46, coil 42, loop 44, bolt 47, loop 45, coil 43, rivets 46, plate 32 and conductor 62.

Laminæ 33 and plates 31 and 32 are provided with aligned holes 62, 63 and 64 respectively. The holes 63 in the laminæ 33 are substantially the same diameter as that of the shank of the bolt 27 whereby the unit 30 is located properly with respect to head 20 and intake 23. The holes 63 and 64 in 45 the conductor plates are somewhat larger in diameter than the shanks of the bolts 27 whereby the plates 31 and 32 will not engage said bolts.

Certain advantages are apparent in the 50 present invention, one of which is the provision of a heating coil unit which can be inserted between the cylinder head of an engine and the intake, the electrical connection therefor extending from the unit 55 between these members whereby it is not necessary to provide separate electrical conduits for terminals in the head or mixing valve.

The entire unit can be assembled before 60 placing same in position and is held in fixed position by bolts which also are used for securing the intake 23 to the head 22.

While the form of embodiment of the 65 invention as herein disclosed, constitutes a preferred form, it is to be understood that

other forms might be adopted, all coming within the scope of the claims which follow.

What is claimed is as follows:

1. A fuel heating unit, comprising in combination, a pair of parallel electrical conductor plates, an insulating member between said plates, a heating element having one end connected to one of said plates, and means for supporting said element by and from said plates, said means including a bolt connected to the other end of said element and to the other plate. 75

2. A fuel heating unit, comprising in combination, a pair of parallel electrical conductor plates, an insulating member between 80 said plates, a heating element having one end connected to one of said plates, an insulator carried by said plate for carrying said heating element, and a bolt for holding the insulator in engagement with said plates, and for electrically connecting the other end of said heating element to the other plate. 85

3. A fuel heating unit, comprising in combination, a pair of parallel electrical conductor plates, an insulating member between said plates, a heating element having one end connected to one of said plates, an insulating spool for carrying said heating element, and a bolt extending through said spool 90 for supporting the heating element and for electrically connecting the other end of the element to the other plate. 95

4. A fuel heating unit, comprising in combination, a plurality of electrical conductor plates insulated from one another, a plurality of heating elements each having one end connected to a conductor plate, and an electrical conductor for attaching said heating elements to said plates and for connecting the other ends of said heating elements. 100

5. A fuel heating unit, comprising in combination, a plurality of electrical conductor plates insulated from one another, a plurality of heating elements each having one end connected to a conductor plate, and a plurality of insulating elements for carrying said heating elements, and an electrical conductor element for supporting the insulating elements and for electrically connecting the other ends of said heating elements. 110

6. A fuel heating unit, comprising in combination, a plurality of electrical conductor plates insulated from one another, a plurality of heating elements each having one end connected to a conductor plate, a plurality of aligned non-conducting spools for carrying said heating elements, and a conducting rod extending through said spools 120 and connected to the other ends of said heating elements and clamping the spools to the plates. 125

7. A fuel heating unit, comprising in combination, a conductor lamina having holes 130

located on opposite sides of a center line of said lamina, one of said holes being larger in diameter than the other, a second conductor lamina similar to the first but inverted whereby the larger hole in one lamina is in alignment with smaller holes in the other, insulating laminæ between and on opposite sides of said conductor lamina and having holes in alignment with the holes in the conductor laminæ, and a rivet extending 10 through each set of holes.

In testimony whereof I heretofore affix my signature.

FRANK F. STARR.
